UNITED STATES PATENT OFFICE.

EDWARD S. BLACK, OF CHICAGO, ILLINOIS, ASSIGNOR TO EDGAR ALLEN AMERICAN MANGANESE STEEL COMPANY, OF AUGUSTA, MAINE, A CORPORATION OF MAINE.

MILL-PINION.

1,171,498.

Specification of Letters Patent. Patented Feb. 15, 1916.

Application filed October 16, 1915. Serial No. 56,200.

To all whom it may concern:

Be it known that I, EDWARD S. BLACK, a citizen of the United States, and a resident of Chicago, in the county of Cook and State 5 of Illinois, have made and invented certain new and useful Improvements in Mill-Pinions, of which the following is a specification.

This invention relates to mill pinions and 10 mill rolls, and more particularly to that class or type thereof which are formed of two or more parts, the object being to so construct and arrange the parts that they may be most securely held together, whereby the mill 15 pinions or rolls will possess the rigidity and advantages of an integral pinion. In attaining the afore-mentioned object, due provision is made for the casting within the drag end of the mold, those parts of the pinion which will be subjected to excessive 20 strains, this feature being of particular importance in the forming of pinions of manganese steel.

A further object is to provide the parts 25 which go to make up the completed pinion of such design and arrangement that they can be economically cast, and easily fitted together, and when so secured, will efficiently resist all end thrusts which tend to change 30 the overall length of the pinion, and other stresses to which the pinion will be necessarily exposed during service.

Other objects and advantages will appear 35 as the description proceeds, wherein it is to be understood that changes in the precise embodiment of the invention can be made within the scope of what is claimed, without departing from the spirit thereof.

The preferred embodiment of my invention 40 is disclosed in the accompanying drawings, wherein:

Figure 1 is a view in longitudinal section of a mill pinion embodying my invention; Fig. 2 is a sectional view thereof taken on, 45 the line 2-2 of Fig. 1; Fig. 3 is a view in longitudinal section of a slightly modified form of connection between the two parts of the pinion; Fig. 4 is a view in section taken on the line 4-4 of Fig. 3; Fig. 5 is a view in 50 longitudinal section of a somewhat further modified form of mill pinion, the connection or securing between the parts being established by a third member or sleeve upon which the parts of the pinion are shrunk, 55 and to which they are keyed; Fig. 6 is a

view in section taken on the line 6-6 of Fig. 5; Fig. 7 is a view in longitudinal section of a further modification of the mill pinion, and Fig. 8 is a view in section taken on the line 8-8 of Fig. 7.

Referring specifically to Figs. 1 and 2, the mill pinion as therein disclosed, is formed with the toothed shells 10-11, from the remote extremities of which project the half-shafts 12-13. These half-shafts each 60 include a bearing portion 14, and power transmitting end 15. The inner or meeting extremities of the toothed shells which conjointly form the mill pinion, considered in connection with the projecting half-shafts, 65 are securely held together and in alinement by the provision of a sleeve 16 which is cast integral with the toothed shell 10 and projects longitudinally therefrom. The sleeve 70 16 is of such external diameter that it can be forced within the extremity of the toothed shell 11, or the latter may be shrunk thereon. The half-shafts are cored as at 17, as is customary, and in connection with the hollow 75 toothed shells 10-11 and hollow sleeve 16, 80 provide a comparatively light, but extremely rigid, construction.

The toothed shells are provided with the longitudinally extending alined openings 18, through which suitable holding bolts 19 extend, whereby the two portions which go to 85 make up the complete mill pinion are securely held together, there being suitable recesses 20 formed within the toothed shells for the reception of the bolt heads and nuts. 90 Should either of the half-shafts which are formed integral with the toothed shells become broken in service, the entire pinion need not be discarded, but a new half-shaft and integral shell may be substituted for 95 that which failed.

A somewhat similar form of mill pinion is disclosed in Figs. 3 and 4, wherein it will be observed that the sleeve 16' which is formed integral with the toothed shell 10', 100 is adapted to fit within a suitable recess 21 which is formed within the extremity of the other of the toothed shells 11'. Suitable holding bolts 18' are utilized to hold the two portions of the pinion together, as in 105 the above-described form. The weight of this latter pinion is somewhat reduced, inasmuch as the shell 11' is provided with a recess into which the sleeve 21 of the shell 10' extends.

A mill pinion embodying somewhat similar features is disclosed in Figs. 5 and 6, wherein the half-shafts 22-23 are formed integral with the toothed shells 24-25, as 5 was the case in the form previously described. A separate sleeve 26, however, is inserted within the meeting extremities of the toothed shells, the shells being shrunk thereon, whereby the two portions of the 10 pinion are held in their proper relative positions. A key 26' is employed in this connection, and further assists in holding the two portions of the pinion against displacement.

15 A further type of mill pinion which is formed in more than one part, is disclosed in Figs. 7 and 8, wherein a single toothed shell 27 is cast integral with the half-shaft 28, the other half-shaft 29 being provided 20 with a sleeve portion 30 which fits within, and extends substantially the entire length of, the toothed shell 27. A key 31 engages the sleeve 30 and the toothed shell 27, and prevents the relative displacement of the 25 parts. In addition to the holding action of the key 31, the toothed shell is preferably shrunk upon the sleeve 30 of the half-shaft 29, so that a most secure holding action and 30 rigid securing between the two, will be effected. The free extremity of the shell 27 is provided with the annular recess 32, into 35 which the shoulder or flange 33 of the half-shaft 29 extends, thus positively preventing the changing of the overall dimension of the pinion, due to end thrusts.

From the foregoing it will be apparent 40 that I have provided for the formation of mill pinions in two separate parts, the parts being secured together by such means as will positively prevent the overall dimensions thereof from being changed by end 45 thrusts, and furthermore, should any portion of the pinion become broken, the broken part may be removed and a new one substituted therefor. Furthermore, the 50 two portions which go to make up the completed pinion may be cast of manganese steel and so arranged within the mold that that portion of the pinion which is particularly susceptible to failure, may occupy the drag end of the mold, and thus possess the requisite strength. Furthermore, there will 55 be no danger of the toothed shell moving along the shaft, as has heretofore happened, the shell in the present instance being formed as a part of, and integral with, the shaft itself. It is to be understood in connection with the foregoing that, although 60 the invention has been particularly described as being a mill pinion, it will be

readily appreciated that the construction is equally adaptable for the formation of mill rolls, where the shell is subjected to tangential and other forces similar to the forces exerted upon the teeth of the pinion described. 65

What I claim is:

1. An article of the class described comprising a shell, a half-shaft formed integral therewith provided with a power transmitting end, and a second half-shaft secured to said shell and held in alinement with the first-mentioned half-shaft thereby and provided with a power transmitting end. 70

2. An article of the class described comprising a shell, a half-shaft formed integral therewith, and a second half-shaft secured to said shell and held in alinement with the first-mentioned half-shaft thereby, the remote extremities of said half-shafts being 80 formed with journal portions and with power transmitting ends. 75

3. A mill pinion formed of cast manganese steel, and including a toothed shell with a half-shaft cast integral therewith, a second half-shaft, and means securing said second half-shaft to said shell and in alinement with the first-mentioned half-shaft. 85

4. A mill pinion formed of cast manganese steel, and including a toothed shell 90 with a half-shaft cast integral therewith, a second half-shaft, and means securing said second half-shaft to said shell and in alinement with the first-mentioned half-shaft, the remote extremities of said half-shafts 95 being formed with power-transmitting ends. 100

5. An article of the class described, comprising a shell, a hollow half-shaft formed integral therewith, and projecting from the one end thereof, a second hollow half-shaft 100 secured to said shell and held in alinement with the first-mentioned half-shaft thereby, said half-shafts provided with journal portions. 105

6. An article of the class described, comprising a shell, a hollow half-shaft formed integral therewith, and projecting from the one end thereof, a second shell and a hollow half shaft formed integral therewith, and means for holding said shells and half-shafts together, and in alinement, said half-shafts provided with journal portions and power transmitting ends. 110

Signed at Chicago, in the county of Cook and State of Illinois, this 6th day of October A. D. 1915. 115
